FLUID SUPPLY

John Leonard Taylor, Milwaukee, Wis.

Application April 24, 1933, Serial No. 667,631

8 Claims. (Cl. 261—18)

The present invention relates to improvements in a fluid supply, and an object of the invention is to generally improve the construction and operation of devices of this class.

5 A further object is to provide a device which will produce a mixture of a liquid and a gas, such for example as oil and air.

A further object is to provide a novel method of producing such a mixture.

10 A further object is to provide such a device which will operate independently of heat.

A further object is to provide such a device which will operate to produce such a mixture by purely mechanical means.

15 More specifically, an object is to provide for atomizing the liquid used in such a manner that it will remain in suspension in the gas substantially permanently, and in any event long enough to be utilized in its suspended state.

20 A further object is to supply a spray nozzle capable of forming a spray of this character.

A further object is to provide a system for the use of such a nozzle.

A further object is to provide in such a system means for supplying the nozzle with fluid.

25 A further object is to provide such means which are capable of caring for unavoidable leakage and condensation within the apparatus.

A further object is to provide such a device 30 which is particularly adapted to furnish fuel and air mixtures for combustion purposes.

A further object is to provide for introducing moisture into the air supply.

A further object is to provide for a convenient 35 power supply for the apparatus.

A further object is to provide for readily and accurately controlling the proportions of fuel and air in the mixture.

40 A further object is to provide for automatically controlling the proportion of moisture in the mixture.

A further object is to provide for automatically controlling the proportions of fuel and moisture in the resulting mixture.

45 A further object is to provide for the use of certain auxiliary devices or appurtenances where desirable for special purposes, and further objects and advantages will be apparent from the following specification and accompanying drawings, in which:

Fig. 1 is a side elevation of an embodiment of the invention shown attached to a known type of internal combustion engine, parts of the apparatus being broken away to show the interior.

Fig. 2 is a central vertical sectional view of the mixing chamber of my invention.

Fig. 3 is a plan view of the part shown in Fig. 2.

Fig. 4 is a horizontal section taken on the line 4—4 of Fig. 2.

Fig. 5 is a plan view of the fuel pump shown in Fig. 1.

Fig. 6 is a front end elevation of the same.

Fig. 7 is a vertical sectional view on the line 7—7 of Fig. 5.

Fig. 8 is a horizontal sectional view on the line 8—8 of Fig. 2.

Fig. 9 is a similar view taken on the line 9—9 of Fig. 2.

Fig. 10 is a sectional detail taken on the line 10—10 in Fig. 1.

Fig. 11 is a detail view of parts indicated in Fig. 10.

Fig. 12 is a sectional view on the line 12—12 of Fig. 1.

Fig. 13 is a sectional view on the line 13—13 of Fig. 1.

Fig. 14 is a fragmentary vertical sectional view similar to Fig. 2 showing a modification of the mixing chamber structure.

Fig. 15 is a sectional view on the line 15—15 of Fig. 14.

Fig. 16 is a fragmentary vertical sectional view showing a further modification of the mixing chamber structure.

Similar reference characters have been applied to like parts throughout the specification and the several views of the drawings.

As shown in Fig. 1 the invention comprises my novel atomization fuel supply system generically designated by numeral 10, and it is shown for convenience in explaining its operation and advantages as installed in operative connection with an engine of the type generally used in industry, motor vehicles, motor boats, aircraft, and the like, and generically designated by numeral 11, the engine being indicated in dotted outlines 12—12. The system is to be understood to be applicable to other types of engines than that shown, or to other purposes than supplying fuel to engines, and in fact it is not to be considered to be limited in application to any type of engine, or in fact in any manner except as defined by the subjoined claims.

The present illustrative embodiment includes a spray type carburetor, herein termed the mixing device 13 communicating as shown with the intake passage 14 of the engine, and a fuel pump 15 connected to supply fluid to the mixing device 13. The pump is driven from any convenient

source of power, in the present instance the power being taken from the engine itself through the customary fan belt 16, and fan shaft 17, the pump being mounted for convenient access alongside the engine 11 as for example by screws 11' engaging a flange 12' fixed with or constituting part of the engine.

The mixing device 13 is herein shown as installed in an "up draft" position, but it is to be understood that it can equally well be arranged in a down draft position, that shown being chosen merely for convenience. The mixing device is connected at its upper end by appropriate means such for example as the flanged union 18 to the intake passage 19 by means of screws or other suitable means 20, Fig. 2. The mixing device comprises a closed, or substantially closed chamber generically designated by numeral 20', Figs. 2 and 3, the chamber having an apertured partition 21 disposed in the lower part thereof, an atomizer nozzle 22 extending upwardly through the bottom of the chamber and terminating preferably between the apertures of the partition 21. Nozzle 22 may be supported in any suitable manner, but is shown as extending through a boss 23 fixed with the bottom of the chamber, the nozzle having a flanged union 24, Fig. 4, fixed as by screws or the like 25 with boss 23. Fluid sprayed or atomized by the nozzle 22 may accordingly be picked up by air or other gas circulating through the chamber 20', the air finding its way therein as follows:

In the embodiment disclosed air enters through a filter 26 of appropriate or well known type and passes through a duct 27 formed in a housing generically designated by numeral 28, constituting part of an air moistening or humidifying device. A valve 29 in the present instance of a segmental rotary type, controls ports 30 and 31, opening the one and closing the other according to its rotated position. A portion of the air thus passes through port 30 and the remainder passes downwardly through a passage 32 and enters a body of reticulated, or absorbent material 33 passing upwardly therethrough and through port 31, and meeting the air coming through port 30 in a passage 34.

Fluid for moistening material 33 may be supplied from any convenient source in the present instance shown as a pipe 35 communicating with a valve 36 controlled by a float 37 in suitable manner to maintain a relatively constant liquid level in a chamber 38 into which material 33 depends to receive the moisture. Rotation of valve 29 will accordingly change the proportions of dry and moist air delivered through passage 34, and accordingly the amount of moisture in the air delivered to the engine.

Air from passage 34, passes into a passage or chamber 39 and part of it passes downwardly into a space 21' beneath above mentioned partition 21, passing up through apertures 21a about nozzle 22 to mix with the fluid spray discharged from the nozzle. The remainder of the air passes upwardly through a passage 40 to mix with the carbureted air discharged from chamber 20'. Passage 40 is controlled by a valve 40a in the present instance of the "butterfly" type by which the relative proportions of pure and carbureted air delivered from the device may be controlled.

The carbureted air from chamber 20' passes upwardly through a regulating valve generically designated by numeral 41 into a passage 42 from which it continues through a safety screen 43, 75 and a heating coil 44, from which it is discharged

through a nozzle or venturi 45 into a mixing passage or discharge pipe 46. Pipe 46 is provided with a valve 47 which may be of any suitable type but is shown as of the "butterfly" type, and serves the purpose of the conventional throttle valve. A space 48 between air nozzle 45 and pipe 46 communicates with passage 40 and provides a path for pure air to enter the pipe and mix with the carbureted air coming from chamber 20'.

Valve 41 in the present instance comprises a rotative disc or plate 41a operable in contact with a portion 41b of passage 42 having a plurality of ports 41c therein. Ports 41c may register more or less with similar ports 41d formed in disc 41a (see Fig. 9) in various rotated positions of the disc, and the disc is maintained against portion 41b by suitable means such as a screw 41e. For rotating disc 41a a rod 41f extends into chamber 20' and has a portion pivotally engaged with an extended portion 41g, the portion being maintained in place in portion 41g by means of a cotter pin 41h or the like. Sliding of the rod into and out of the casing accordingly causes rotation of disc 41a and changes the amount of carbureted air passing into nozzle 45. Rod 41f may be controlled in any suitable manner, and, together with valve 40a provides a method of carburetor adjustment permitting accurate control of the resulting fuel mixture.

Screen 43 is of suitable construction to prevent a possible back-fire from igniting the fuel in chamber 20'.

Heating coil 44 comprises a coil of resistance material or the like 44a, Fig. 8, the successive turns of which provide space for the flow of mixture therebetween, a conductor 44b supplying heating current to the coil through a bolt or the like 44c insulated from metal contact by a bushing 44d, the bolt 44c passing into pipe 46, and connecting therein with an extended end 44e of coil 44a.

Nozzle 45 may be of any shape or may have any characteristics which may be found desirable, the shape shown in Fig. 2 being found to give good results, as do also the modifications shown in Figs. 14 and 16. The invention does not depend for novelty upon the particular shape of these parts, and is not limited to the illustrative embodiments shown and described, or in any manner except as defined by the subjoined claims.

The embodiment of Figs. 14 and 15 is generally similar to that of Fig. 2 but in place of the nozzle 45 has a sleeve 45a fixed in a portion 42, and bridging the space 48, the sleeve being provided with a plurality of ports 45b for permitting gas flow from space 48 into intake passage 46. A second sleeve 45c is rotatively fitted in sleeve 45a, and is provided with similar ports 45d which may register more or less with above mentioned ports 45b in various rotated positions of sleeve 45c to regulate the effective opening of the space 48. This gives a further method of regulation of the proportions of the final mixture not possible with the embodiment of Fig. 2. Sleeve 45c has a spanner or other member 45e in the present instance at its lower end, which is fixed with a shaft 45f journaled in a gate member 45g which is provided with ports 45h after the manner of portion 41b of Fig. 2. A disc or plate 45i cooperates with gate 45g and has ports 45j similar to ports 41d of disc 41a which may be disposed with relation to ports 45h to regulate the flow of carbureted air into sleeve 45c. Disc 45i is fixed with a hub portion 45k which is in turn journaled on above mentioned shaft 45f, and the hub is 75

provided with an arm 45^l from which control connections may extend to any convenient point. An arm 45^m is fixed with shaft 45^f for similar purposes.

It might be noted at this point that it is not necessary in the above described embodiments to regulate the output of nozzle 22 with extreme accuracy, the purpose being served if it atomizes sufficient fluid to maintain an over-rich mixture 10 in the chamber 20', this rich mixture being drawn in regulated amounts through the ports of disc 41^a and diluted with fresh air from passage 40, the amount of fresh air being controlled by means such as valve 40^a or sleeve 45^c. The 15 valves 40^a, 41^a, and 47 may for convenience be said to correspond in a sense with those of an ordinary carburetor, but it is to be understood that the operation of the present device is entirely distinct from those devices which depend 20 upon vaporization for their action, the present apparatus operating successfully with fuels having a vaporization temperature far in excess of the temperature of the air passing through the device.

25 The heating coil 44 is not used continuously during the operation of the device, but is provided for heating the mixture to facilitate starting an engine connected to the device.

The modification shown in Fig. 16 is similar to 30 the embodiment shown in Fig. 2 with the exception that the nozzle 45, instead of tapering at the top as shown in the prior embodiment has a flaring upper outlet or Venturi portion 45ⁿ. This gives somewhat different characteristics of operation 35 from the other types, and is found in certain instances to give superior operation. Such details as this, however, do not constitute the essence of the invention, the same being concerned with an entirely new method of supplying a fluid mixture, 40 insofar as I am aware.

As above suggested the method does not depend upon heat, but in the illustrative embodiment it depends upon the action of a new type of atomizer nozzle of my invention, and which in itself 45 is the subject of a separate application for Letters Patent, filed March 25, 1933, Serial No. 662,673 for Atomizer and of which this application is a continuation. This nozzle (22 in the present drawings) is supplied with fluid under relatively 50 high pressure and is capable of reducing it to an impalpably fine mist or spray, so fine as to remain substantially permanently in suspension in air, the particles having no noticeable tendency to settle or coalesce into larger particles.

55 While the very fineness of the particles of fluid is instrumental in causing them to remain suspended in this manner, there is evidence to warrant the conclusion that the particles, owing to the friction to which they are subjected in escaping from the nozzle or for other reasons, acquire an electric charge of similar sign and consequently actively repel each other so long as this charge is not dissipated.

The resulting suspension may be treated and 60 handled, and operates substantially as a perfect gas, the difficulties of condensation encountered in ordinary carburetors being conspicuously absent. The suspended fuel mixture is accordingly throttled, diluted, and utilized as above described without certain of the difficulties usually 65 encountered, and with numerous advantages which will appear more fully below.

Nozzle 22 comprises a body portion 49, Fig. 2, which in the present instance is substantially 70 cylindrical, and is mounted in an upright position

for convenience in the bottom wall of chamber 20', the body having a suitable bore in which is slidably fitted a stem, plunger, or piston 50 having a head 51 which is yieldably maintained in a downward direction against a seat 52 formed on or fixed with body 49. The space formed between head 51 and seat 52 upon yielding of stem 50 constitutes the spraying orifice of the nozzle. Stem 50 is downwardly urged by a spring 53 acting against a nut 54 adjustably engaging a 10 threaded extension 55 of stem 50, the nut being formed in the present instance at 56 for engagement of a spanner, wrench, or the like, for ready adjustment thereof. A lock nut 57 engages a tapered extension 58 of nut 54 the extension being 15 arranged to be compressed against the threads of stem extension 55 to prevent undesired displacement of nut 54. The whole is assembled in a bore 20 in body portion 49, the bore being closed by a cap or plug member 60, which is preferably readily removable. A sleeve portion 60^a of body member 49 depends into bore 59, and acts as a stop to limit the upward movement of stem 50, above mentioned nut 54 engaging the end of the sleeve upon predetermined movement of the stem. The 25 maximum permissible opening of the spray orifice may thus be accurately determined by the setting of nut 54, and in practice this opening is very small, for example on the order of quarter of a thousandth of an inch. The peculiar formation 30 of the nut 54 and the lock nut 57 permits relatively very accurate adjustment of this clearance as explained in the above mentioned co-pending case, and is in a measure responsible for the novel results secured by the atomizer.

The thickness of the sheet of fluid escaping from the orifice is preferably adjusted to be equal to or less than that of a natural film of the fluid, such a film for example as that constituting the wall of a bubble formed of the fluid and freely 35 supporting itself in air.

Fluid supplied to the atomizer from the pump which will be described presently is conducted to an annular chamber 61 in body 49 beneath head 51, the fluid coming from the pump in a conduit which is connected at 62, a boss 63 or the like being provided on body 49 for this purpose. A suitable passage 64 leads upwardly from boss 63 to chamber 61 through which fluid may find access to the spray orifice. The seat 52 is formed of greater diameter than the plunger 50, and fluid pressure in chamber 61 will accordingly have an unbalanced upward component of pressure on the plunger. A high enough fluid pressure will thus cause upward movement of the plunger and opening of the orifice, the pressure overcoming the force of spring 53 and the upward movement being limited by the stop sleeve 60^a. A certain amount of fluid will unavoidably leak downwardly around plunger 50, finding its way eventually 50 into bore 59, from which it escapes through a passage 59^a communicating with a connection 65 provided to receive a discharge pipe or the like, which may be connected for recovering the escaped fluid, or otherwise disposing of it.

A connection 69 is provided in chamber 20' for the attachment of a drain pipe when the device is used for down draft operation, there being an opening 69^a leading therefrom into the interior of the chamber, it being understood that the device will work equally well in an inverted position, the humidifier, however remaining in the position shown, and the casing 13 being rotated relatively thereto about passage 34. Owing to the disposition of this passage the humidifier re- 70 75

mains in satisfactory relation to casing 13 whether the latter is in the position shown, or reversed.

Pump 15 is driven as above noted from engine 12, the pump having a shaft 70 driving a shaft 71 through a pinion 72 meshing with a gear 73, the pinion and gear being fixed respectively with shafts 70 and 71. Shaft 70 carries a pulley 74 which is driven in the present instance from a pulley 75 fixed with above mentioned fan shaft 17 by means of a belt 76. Shaft 71 is suitably journaled in a shaft housing 77, to which is properly secured a housing 78 for gears 73 and 72, an oil retaining closure 79 being provided to seal the space about shaft 70. The major portion of the pump is in the form of a cylinder block 80 providing a plurality of cylinders 81, 82, 83, and 84. The cylinders have reciprocably fitted therein plungers or pistons, 85, 86, 87, and 88, respectively, the plungers being provided with suitable actuating means, in the present instance in the form of flat cam followers 89, and each plunger has a spring 90 disposed about its respective cylinder and acting between a shoulder 91 in block 80 and a follower 89 to urge the plunger out of the cylinder. Shoulder 91 is the upper wall of a chamber 92 in block 80 in which cylinders 81 to 84 are disposed, the cylinders in the present instance being formed separately from the block 30 and inserted therein subsequently. Actuating means for plungers 86, 87, and 88 are provided in the form of cams 93, 94, and 95, coacting with the followers attached to the respective plungers, and plunger 85 is actuated from a rock shaft 96, Fig. 35 7, which may be manually operated by means of suitable connections or the like engaging a lever 97 provided with an opening 98 for the purpose. Rock shaft 96 is journaled in suitable bearings 99 and 100 disposed in housing 77, and the shaft 40 is provided with a flattened cam surface 101 engaging cam follower 89 on plunger 85, rocking of the shaft raising the plunger against the resistance of the spring 90. Antifriction bearings 102 and 103 carry shaft 71, and similar antifriction bearings 104 and 105 carry shaft 70. Closure 79 is held in place by suitable means such as screws 107, while housing 78 is maintained in place by similar screws 108. Shaft housing 77 has a flange 109 engaging a suitable flange on block 80, a gasket or the like 110 being interposed to render the joint fluid tight in familiar manner. The housing and block are held together by screws 111, and 111'.

The fluid, in its course through the pump is 55 controlled by check valves as shown particularly in Figs. 5, 6, and 7. The arrangement of the valves for the several cylinders being the same in the present embodiment, only one will be described, since the arrangement of the others can 60 be readily ascertained therefrom.

Fluid is supplied from a general supply tank not shown through a supply pipe 112 which communicates with a passage 113 formed in block 80 and constitutes a supply for cylinders 81, 82, and 65 83, cylinder 84 being otherwise supplied as will presently appear. Referring to Fig. 7, the fluid passes downwardly upon the suction stroke of the pump plunger 85 through a bore 114 in a bushing 115, the bore being closed against flow in an upward direction by a ball or other valve member 116 seated against the lower rim of the port opening and yieldably held thereagainst by a spring 116a seated against the upper end of the removable cylinder 81. The discharge stroke of the 75 plunger assists spring 116a to force valve 116

against its seat, and prevent escape of fluid into the supply passage. The fluid, accordingly, passes through a duct 117 in block 80 and upwardly through a port 117a in a seat member 118 against which is seated a valve member in the form of a ball 119 yieldably maintained against the seat by spring 119a, the spring bearing upwardly against an apertured stop member 120 suitably fixed in a bore 120a forming a housing for the valve parts. The bores 120a and 120b are closed by suitable 10 plugs, caps, or the like 121 and 122. Fluid passing valve 119 enters a passage 123 from which it is finally delivered to nozzle 22.

To maintain a substantially steady pressure at the nozzle means are provided in the present instance in the form of an accumulator having a cylinder 124 provided with a piston or plunger 125, the piston being forced upwardly by a member 126 urged by a spring 127 enclosed in and bearing against a housing 128 removably fixed with block 80. Fluid pressure in passage 123 acts through a passage 129, Fig. 5, and a port 130 on the upper end of plunger 125 and when, under the impulses of pump 15 it reaches a sufficiently high value, it depresses the plunger 23 against the resistance of spring 127, the plunger moving up and down to absorb any irregularity in the delivery of the pump, and serving as a momentary storage chamber for fluid for supplying the nozzle 22. Pump cylinders 82 and 83 also deliver into passage 123, and at certain speeds of engine 11 it is conceivable that the rate of delivery might exceed the discharge capacity of nozzle 22 at the desired pressure, whereupon excessive pressure would be developed in the fluid passages. Various means may be utilized to guard against such a contingency, but in the present instance cylinder 124 is provided with a relief port 132 which is normally closed by piston 125, but which is opened or uncovered 40 by the piston near the limit of the down stroke thereof. Spring 127 is chosen of a suitable strength to yield at a desired normal working pressure of fluid, and this pressure is never exceeded owing to the action of the relief port 45 as just described. Fluid finding its way into housing 128 either through port 132 or through the unavoidable leakage past the piston 125 passes into the shaft housing 77 through a duct 133 in the present instance formed in block 80, 50 and is disposed of as will presently appear. The fluid is conducted from passage 123 to nozzle 22 through a pipe 134 which connects with the nozzle at 62 as above suggested.

Although the fluid sprayed into chamber 20' 55 does not condense to any extent on the walls of the chamber, or upon those of the connecting passage, there may be some accumulation of liquid on the walls of chamber 20' particularly where the spray contacts the walls, this liquid eventually running down the same, and finding its way through the openings 21 into space 21', from which it is drained through an opening 135, preferably threaded for connection of pipe 137, which leads, as particularly shown in Figs. 1 and 5, into a portion of block 80 comprising the suction valve of cylinder 84, this valve being, as above explained identical with the valve 116 of cylinder 81. The fluid discharged from cylinder 84 passes through a valve which is identical with valve 119 of cylinder 81, and returns through a pipe 138 to the general supply tank, or may be returned to the suction pipe 112, or 70 may be otherwise disposed of in suitable manner. A pipe 139 leads from connection 65 of nozzle 75

body 49, and connects as shown with pipe 137 thus returning leakage from the nozzle plunger 50 to the suction of pump cylinder 84, and a connection 140 leads from the interior of housing 78 and connects with pipe 137 by means of a T connection 141. Fluid drained into shaft housing 77 is accordingly recovered by pump 84 and returned to the supply tank or otherwise disposed of.

10 It is understood that minor changes in the details of construction may be made without departing from the invention, and that the same is not limited to the details of construction disclosed. For example, plungers 85, 86, 87, and 88 are 15 shown of various diameters in accordance with the duties each has to perform, plunger 85 being of small size to give a high pressure with a minimum of actuating force, plungers 86 and 87 being larger to deliver a larger volume under 20 running conditions when plenty of power is required and available, and plunger 88 being still larger to handle a large volume of fluid where a high delivery pressure is unnecessary. Other 25 expedients may be used to obtain this effect without departing from the invention. Similarly the spring loaded accumulator might be replaced with some other suitable means capable of giving a substantially constant pressure at nozzle 22 without departing from the invention.

30 The apparatus so far disclosed could be operated to supply a fuel mixture for an internal combustion engine or for other purposes, the valve 47 serving to throttle the flow of mixture to the engine, the valve disc 41, particularly in 35 conjunction with valve 40a serving to control the quality, or richness of the mixture, and the valve 29 operating to control the amount of moisture in the mixture. These may of course be operated independently but it is usually desirable to cause them to work together in some definite relation so that operation of the throttle 47, for example, will cause such adjustments of others of the valves as to maintain proper mixture conditions for various throttle settings. 45 This may be done in a number of ways, many of which are well known, but for convenience in illustration valves 29, 40a, and 47 are shown connected by suitable adjustable links.

Referring to Fig. 1, throttle valve 47 has a 50 shaft 142 fixed therewith carrying, outside of intake pipe 46 a lever arm 143 operable from an actuating rod 144 pivotally connected to the lever as particularly shown in Fig. 12, and a link 145 is connected to actuate valve 40a and 29. Valve 55 40a has a shaft 146 fixed therewith carrying a lever arm 147 to which link 145 is pivoted, and a similar link 148 pivoted to lever 147 actuates a lever arm 149 fixed with a trunnion 150 fixed with valve 29.

60 The links are adjustable in effective length, the construction being as follows: Throttle actuating rod 144 pivotally engages a bushing 151 journaled in a bore in arm 143 (Fig. 12), the bushing having a bolt 152 extending therethrough 65 and, through a slot 153 in link 145, a nut 154, clamping the bushing rigidly with the link in various desired positions. To prevent undesired rotation of the nut, a key portion 155 particularly shown in Fig. 11 is formed on the nut or fixed 70 therewith engaging the slot. The relation of valves 40a and 29 to throttle valve 47 can accordingly be predetermined and automatically maintained by suitably adjusting the position of bolt 152 in the slot. Link 145 operates upon a pivot 75 fixed with lever 147, in the present instance com-

prising a bolt 156, Fig. 13, rigidly fixed with the lever, and about which pivot both links 145 and 148. Any other suitable construction may be used at this point, that shown being simple and effective. Link 148 is adjustable relatively to lever arm 149, the construction being similar to that used in connection with lever arm 144. A bushing 157 is suitably journaled in arm 149 and clamped in engagement with link 148 by means of a bolt 158 having a nut 154 as above described 10 providing a key portion 155 engaging a slot 159 formed in link 148. By suitably adjusting the bolts 152 and 158 the relations between the three valves may be changed at will. Valve 41 is ordinarily connected for separate adjustment, but if desired it could be connected for operation from the above linkage in any suitable manner without departing from the present invention. Also if desired appropriate connections could be made to the levers 457 and 45m in the embodiment of 15 Fig. 14 if it were desired to automatically operate the valves 45c and 45j, all within the province of the present invention.

The regulation of the quality of the resulting mixture may be effected in other ways than by the various valves in the air passages. For some applications this would be desirable and as illustrating a suitable alternative method a valve 134a, Fig. 14, of a needle or other suitable type is 20 interposed in the liquid pipe 134 to control the flow of liquid to nozzle 22. By this means the proportion of liquid in the mixture can be directly regulated, either in conjunction with the regulation of the air passages or independently thereof. It is desirable that valve 134a be operated 25 independently with the main throttle valve 47, and for this purpose in the present instance it is shown mechanically connected therewith.

Throttle shaft 142 in this embodiment has a rearward extension and has fixed therewith a lever arm 134b actuating through a suitable pivot member 134c a link or the like 134d which extends downwardly as shown to actuate through a lever arm 134e a stem member 134f of valve 134a. Link 134d is provided with a slot 134g in which 30 is adjustably clamped a bolt and its associated elements generically designated by numeral 134h and preferably substantially identical with bolt 158 above described. The bolt and its associated 35 elements form a suitable pivotal connection between link 134d and lever 134e, and one which when loosened may be displaced in slot 134g to change the relation between levers 134e and 134b. In the present instance lever 134e is clamped to 40 stem portion 134f, the lever being bifurcated as 45 shown and the halves urged into clamping engagement with the stem by means of a screw 134i. The relation between the lever and the 50 valve elements may thus be changed as well as that between the lever and the link, so that substantially any desirable relation or ratio of movement between throttle 47 and valve 134a may be 55 readily obtained.

With this arrangement the amount of liquid sprayed may be adjusted to correspond properly 60 with the amount of air admitted to the engine by the throttle 47, and the whole of the sprayed liquid will be taken up by the air stream. It is not necessary to spray an excess of liquid, and the wear on the nozzle 22, and the power necessary for pumping are reduced. With this arrangement one or another or all of valves 40a, 65 41, 45j, or 45c may be eliminated, and this is contemplated as within the scope of the invention. 70

The operation of the invention is conveniently described in connection with an internal combustion engine, although as above noted the system of introducing a permanent suspension of a liquid into a gas is applicable to other situations or uses, and all such uses are considered as within the scope of the invention except as limited by the claims. When it is desired to start the engine pump 81 is operated by means of the control or actuating lever 97 to build up a pressure in pipe 134, the fluid spraying from the nozzle 22 in exceedingly fine particles, most or all of which remain suspended in the air in chamber 21' forming an easily ignited explosive mixture. The engine is then turned over in the usual manner whereupon the suction in the intake pipe 46 draws the mixture through valve 41, nozzle 45, and past throttle valve 47 into the engine intake pipe 14, the mixture firing in the engine and operating the engine in the conventional manner. As soon as the engine starts, its motion is transmitted through belts 16 and 16 to the pump mechanism and operates pumps 82 and 83, which supply a continuous flow of fluid for nozzle 22, thereby maintaining the supply of suspended liquid in chamber 20', leakage and condensation being returned to the supply tank by pump 84. As the engine changes speed the pump changes speed also, and the proportions of the parts are such that the amount of fluid pumped is always in excess of the amount required by the engine, the amount permitted to go to the engine being regulated by the throttle 47, and the quality of the mixture being controlled by the valves 40a and 29. A steady pressure at nozzle 22 is insured by the storage of fluid in the accumulator cylinder 124, and this cylinder also serves to prolong the spraying somewhat after the operation of the hand pump 81.

It has been found that a relatively high percentage of moisture can be introduced through the humidifier apparatus 33 etc. particularly when the engine is under heavy loads, with conspicuous advantages as to capacity and economy of the engine, and the connection between the throttle 47 and the valve 29 permits full advantage to be taken of this fact. In practice the apparatus of the present invention has been found to permit the burning of relatively heavy fuel oils in engines primarily intended and designed to use much lighter fuels such as gasoline and the like, and to do this with an increase in the capacity of the engine and a decrease in the amount of fuel consumed per unit of power developed.

The above being a full and clear disclosure of an illustrative embodiment of the apparatus by which the above results and advantages may be realized, what is claimed as new and desired to be secured by Letters Patent of the United States is:

1. In a fuel supply for a gas engine the combination of a mixture inlet pipe, a throttle valve controlling the flow through said pipe, a mixing chamber communicating with said pipe, an air inlet for said chamber, a fuel supply, an atomizer nozzle disposed to form a dispersion of fuel in said chamber, a power driven pump connected with said nozzle and operable to supply fuel from said supply to said nozzle, an auxiliary air inlet positioned to supply air to said mixture inlet pipe independently of said mixing chamber, valve means arranged to regulate the flow of air through said auxiliary air inlet, and connections operative to independently actuate said throttle and said valve.

2. In a fuel supply for a gas engine the combination of a mixture inlet pipe, a throttle valve controlling the flow of mixture through said pipe, a mixing chamber communicating with said pipe, an air inlet for said chamber, a fuel supply, an atomizer nozzle disposed to form a dispersion of fuel in said chamber for mixing with said air, a power driven pump connected to pump fuel from said supply to said nozzle, a fuel control valve operative to regulate the flow of fuel through said atomizer nozzle, and connections operative to independently actuate said throttle and said fuel control valve.

3. In a fluid supply a humidifier including an air inlet, and a humidified air outlet, and a humidifying conduit, means in said conduit for humidifying air passing therethrough, a passageway for air directly from said inlet to said outlet, and movable valve means positioned to partially intercept both said passageway and said conduit for dividing air entering said inlet as desired between said passageway and said humidifying conduit.

4. In a fuel supply for a gas engine the combination of a carburetor having a throttle valve controlling the flow of mixture therefrom, a humidifier including a humidifying conduit, means in said conduit for humidifying air passing therethrough, a passageway for air directly to said carburetor independently of said humidifying conduit, valve means arranged for dividing air passing through said humidifier between said humidifying conduit and said passageway, and connections from said throttle valve for independently operating said throttle valve and said valve means.

5. In a carburetor a nozzle casing having an outlet opening in one end and a nozzle supporting opening, said casing having an air inlet in one side directed substantially at right angles to said outlet opening, and a humidifier including a humidifying conduit and a liquid reservoir, said humidifier having a substantially horizontal air outlet registering with said air inlet, and arranged for engagement therewith in various relative rotated positions whereby said casing may be applied to an engine with said outlet directed alternatively upwardly or downwardly and support said humidifier with said liquid reservoir in an upright position.

6. In a fluid supply a humidifier including a substantially vertical conduit, a fluid reservoir beneath said conduit and spaced therefrom to provide an opening, absorbent material in said conduit and extending across said opening into said reservoir, means for maintaining a supply of fluid in said reservoir, and means for causing a draft of air in at said opening and up through said absorbent material.

7. In a fuel supply for a gas engine the combination of a mixture inlet pipe, a throttle valve controlling the flow of a mixture through said pipe, a mixing chamber communicating with said pipe, an air inlet for said chamber, a fuel supply, an atomizer nozzle disposed to form a dispersion of fuel in said chamber for mixing with said air, a power driven pump connected to pump fuel from said supply to said nozzle, a fuel control valve arranged to regulate the flow of fuel through said atomizer nozzle, and means dependent upon the setting of said throttle for setting said fuel control valve in accordance with the setting of said throttle.

8. In a fuel supply for a gas engine the combination of a mixture inlet pipe, a throttle valve

controlling the flow of mixture through said pipe, a mixing chamber communicating with said pipe, an air inlet for said chamber, a fuel supply, an atomizer nozzle disposed to form a dispersion of fuel in said chamber for mixing with said air, a power driven pump connected to pump fuel from said supply to said nozzle, fuel control

means arranged to regulate the flow of fuel through said atomizer nozzle, and means responsive to changes in the setting of said throttle and arranged to change the setting of said flow regulating means.

JOHN LEONARD TAYLOR.
